United States Patent

Des. 240,180
Patented June 8, 1976

240,180

FLOWER POT HOLDER

Michael W. K. Young, 45—14 196th St.,
Flushing, N.Y. 11358

Filed May 30, 1975, Ser. No. 582,211

Term of patent 14 years

Int. Cl. D6—04

U.S. Cl. D6—137

Fig. 2.

Fig. 1.

FIG. 1 is a front elevational view of a flower pot holder showing my new design. The flower pot is shown in broken lines for illustrative purposes only;

FIG. 2 is a top plan view thereof;

FIG. 3 is a side elevational view thereof; and

FIG. 4 is a rear elevational view thereof.

I claim:

The ornamental design for a flower pot holder, substantially as shown and described.
